UNITED STATES PATENT OFFICE

2,437,353

AUXILIARY PROPELLER FOR AIRSHIPS AND
HOUSING THEREFOR

Michael Gliwa, Chicago, Ill.

Application June 10, 1946, Serial No. 675,606

3 Claims. (Cl. 244—26)

1

The present invention relates to auxiliary propellers for airships, and has for its main object the provision of a propeller set below the floor of an airship, to be employed either in emergencies or as additional means for lifting the airship in an upright direction.

A still further object of the present invention is the provision of a suitable housing within which the propeller of the type aforesaid may be enclosed when not employed, in order that the propeller may not constitute a drag which otherwise it would if exposed.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views;

Fig. 1 is a fragmentary cross-sectional view on a transverse plane through an airship, showing the auxiliary propeller in an inoperative position, and enclosed within a housing, the view having been taken on line 1—1 of Fig. 2;

Fig. 2 is an elevational bottom view of an airship with a housing enclosing the auxiliary propeller in a closed position; and

Fig. 3 is a side elevational view of the housing when closed.

Referring in detail to the present drawing there is shown therein fuselage 10 of an airship including floor 11 thereof.

Extending transversely through floor 11 is shaft 12, at the lower end of which propeller 13 is rigidly affixed. Said shaft 12 may be connected by any known suitable means either to the main engine of an airship or to an auxiliary engine which may be specially set up and used for rotating said shaft 12. Said means may be either shafts and gears or sprocket chains and sprocket wheels. No showing of means for rotating shaft 12 is made because the same does not constitute the subject-matter of this application.

When propeller 13 is not in use, the same is brought into a longitudinal relation with the airship, as shown by dotted lines in Fig. 2, by manipulating shaft 12 within the airship, and then the housing, presently described, is brought into an operative position for enclosing the propeller so that the same may not constitute a drag when exposed to the air during flight of the

2

airship. Said housing includes a pair of spaced, substantially elliptical hoods 14, which are attached in any suitable manner to the bottom of floor 11, and which are stationary.

Interposed between said hoods 14 is a plurality of oblong panels 15, three of which are set on each side of shaft 12. Panels adjacent floor 11 are hinged to the floor by hinges 16. The remaining two panels 15, on each side of shaft 12 are connected to each other as well as to the first named panels by means of hinges 17. When said panels 15 are closed as shown in Fig. 1, the same substantially assume a semi-annular formation, substantially corresponding to the formation of the inner ends of hoods 14 with which they form substantially smooth surface, devoid of resistance to the air.

For closing said panels 15 and for maintaining the same closed, cords 18 are attached, at points 19 to the pair of innermost panels 15, by means of which all of panels 15 are shifted to the closed position, best shown in Fig. 1. Connecting points 19 for cords 18 are at the extreme terminations of said innermost panels 15, and past the ends of propeller 13 so that said cords 18 may not interfere with the propeller when the same remains in longitudinal position shown in Fig. 1, and enclosed within the housing. No means for drawing cords 18 is shown because any suitable, known means may be provided, such as windlass for winding cords 18 when the housing is to be closed, or unwinding the same when panels 15 are about in the process of opening.

For opening said panels 15 and bringing the same into a flat, planar position shown by dotted lines in Fig. 1, cords 20 are provided. Said cords 20 connect outwardly with the innermost panels and substantially centrally thereof, at points 21. Said cords 20 are drawn over pulleys 22, which are supported upon brackets 23, the latter affixed outwardly to the side walls of fuselage 10, and adjacent floor 11. Cords 20 pass into fuselage 10 through the side walls thereof.

When said cords 20 are drawn into the fuselage, upon first releasing cords 18, the former will draw said panels 15 into their open, flat position, shown by dotted lines in Fig. 1. Means for operating cords 20 is not shown because the same may be of any suitable construction, well known in the art, such as windlass, drums, etc.

It is observed however that when cords 20 are drawn to shift panels 15 into their open position, simultaneously cords 18 are released, and conversely when cords 18 are drawn in order to close panels 15, cords 20 are simultaneously released.

When occasion to use propeller 13 arises such as emergency for the purpose of sustaining an air ship, or as an auxiliary means for adding additional lifting power thereto, panels 15 are open into their inoperative position illustrated by dotted lines in Fig. 1. When this is done propeller may then be caused to rotate without interference from said panels 15. Upon having used propellers 13, the same is brought, by any suitable means, into a longitudinal relation with the housing and thereupon panels 15 are closed by drawing cords 18, for enclosing within panels 15 propeller 13.

The perimeters of hoods 14 substantially correspond to the perimeter of panels 15 when closed, while the outer ends of said hoods 14 are gradually tapering, presenting smooth surface, with the minimum degree of resistance to air.

While there is described herein preferred embodiments of the present invention, it is nevertheless to be understood that minor changes may be made therein without departing from the spirit and scope of the invention as claimed.

What I claim as new is:

1. In an airship having an auxiliary propeller disposed below the floor of the fuselage thereof, a housing for said propeller comprising a pair of spaced, stationary hoods, said propeller being disposed between said hoods, a pair of series of panels, the innermost panel in each series being hingedly connected to the floor of the fuselage, the panels in each series being hingedly connected to each other, all of said panels being disposed between said hoods in a longitudinal relation, means for drawing said panels in each series into a planar mutual relation coextensive with the floor of the fuselage for freeing said propeller, and means for drawing said panels in a closed enveloping position around the propeller.

2. In an airship having an auxiliary propeller disposed below the floor of the fuselage thereof, a housing for said propeller comprising a pair of spaced, stationary hoods, said propeller being disposed between said hoods, the space defined by said hoods being of a substantially rectangular formation for positioning said propeller longitudinally of said space when said propeller remains inoperative, a pair of series of panels, each

series thereof being disposed laterally of the propeller when the same remains in said longitudinal position, the innermost panel in each series being hingedly connected to the floor of the fuselage, all panels in each series being hingedly connected to each other, all of said panels being disposed between said hoods in a longitudinal relation, means for drawing said panels of each series into an enveloping position around the propeller when the same remains in said longitudinal position, and means for drawing said panels in each series into a planar mutual relation and out of the path of said propeller.

3. In an airship having an auxiliary propeller disposed below the floor of the fuselage thereof, a housing for said propeller comprising a pair of spaced, stationary hoods, said propeller being disposed between said hoods, the space defined by said hoods being of a substantially rectangular formation for positioning said propeller longitudinally of said space when said propeller remains inoperative, a pair of series of panels, each series thereof being disposed laterally of the propeller when the same remains in said longitudinal position, the innermost panel in each series being hingedly connected to the floor of the fuselage, all panels in each series being hingedly connected to each other, all of said panels being disposed between said hoods in a longitudinal relation, means for drawing said panels of each series into an enveloping position around the propeller when the same remains in said longitudinal position, and means for drawing said panels in each series into a planar mutual relation and out of the path of said propeller, both of said means including cords attached to the outermost panel in each series.

MICHAEL GLIWA.
